PUSH TOY

William R. McLain and Charles H. Hardin, Nashville,
Tenn., assignors to Kusan, Inc., Nashville, Tenn., a
corporation of Kentucky

Filed Mar. 10, 1969, Ser. No. 16,155

Term of patent 14 years

Int. Cl. D21—02

U.S. Cl. D34—15

FIG. 1

FIG. 4

FIG. 2

FIG. 3

FIG. 1 is a front elevational view of the push toy showing our new design;

FIG. 2 is a side elevational view thereof;

FIG. 3 is a rear elevational view thereof; and

FIG. 4 is a top plan view thereof.

Portions of the guide stick have been omitted from FIGS. 3 and 4 for convenience of illustration.

We claim:

The ornamental design for a push toy, as shown and described.
